(57) **CLAIM**

The ornamental design for an external nasal dilator, as shown and described.

DESCRIPTION

FIG. 1 is a top plan view of a first embodiment of the invention.

FIG. 2 is a side view of the first embodiment of the invention as applied across the bridge of a user's nose.

FIG. 3 is a three-quarter perspective view of the first embodiment of the invention.

FIG. 4 is a top plan view of a second embodiment of the invention.

FIG. 5 a side view of the second embodiment of the invention as applied across the bridge of a user's nose; and, FIG. 6 is a three-quarter perspective view of the second embodiment of the invention.

The broken line showing of periphery is for the purpose of illustrating portions of the periphery of the external nasal dilator and forms no part of the claimed design. The broken line showing of human facial features is directed to environment and is for illustrative purposes only; the broken line forms no part of the claimed design.
